UNITED STATES PATENT OFFICE.

JAMES ROTHSCHILD, OF NEW YORK, N. Y.

JEWELRY.

SPECIFICATION forming part of Letters Patent No. 451,661, dated May 5, 1891.

Application filed January 6, 1891. Serial No. 376,851. (No model.)

To all whom it may concern:

Be it known that I, JAMES ROTHSCHILD, a citizen of the United States, residing at New York, in the county of New York and State 5 of New York, have invented certain new and useful Improvements in Jewelry; and I do hereby declare the following to be a full, clear, and exact description of the invention, such as will enable others skilled in the art to which 10 it appertains to make and use the same.

My invention consists in a bracelet adapted to be enlarged in order to be passed over the hand and reduced in circumference when encircling the wrist, and means to maintain the 15 bracelet at a given size when adjusted in place upon the person.

My invention is hereinafter fully described, illustrated in the drawings, and specifically pointed out in the claims.

20 Referring to the accompanying drawings, wherein like letters of reference point out similar parts on each figure, Figure 1 is a perspective view of a bracelet embodying my invention, showing in dotted lines the movable band completely extended, also showing in dotted lines the lock-handle lifted up. Fig. 2 is a sectional view of a portion of the bracelet and sliding band. Fig. 3 is a plan view of a portion of the blank sliding band.

25 30 The main member of the bracelet consists of a hollow section A, having upper plate a , ornamented in any desired style. Said upper plate may have a plain surface, as shown in the drawings, or be corrugated, embossed, or 35 have any desired ornamental configurations. In parallel alignment with said upper plate is an under plate a' , the two being connected by sides a^2 , thus forming a box-section A, which for practical purposes should be about the 40 length to embrace and reach over the upper portion of a wrist.

45 B is an extensible band, which is permanently secured at one end within the section A by soldering or riveting, its other end being loosely inserted into the opposite end of the box, through and within which it is 50 adapted to slide to and fro, whereby, as will be readily understood, the circumferential dimension of the bracelet can be regulated at will. The band can be extended to the extent shown in dotted lines, Fig. 1. It can then be slid within the section A until it assumes

the size and shape shown in full lines, although any intermediate size can be attained by introduction of only a portion of the band 55 B within the section A, and it can be thereat held in place by means presently pointed out.

The free end of the band B is preferably supplied with detents of any suitable form. In Fig. 3 the free end of the band is shown as 60 cut into at each side, to enable portions thereof to be upturned and compose a limiting-stop, consisting of upturned detents b b , but I do not confine myself to this special form of limiting-stop, as it is obvious various analogous 65 mechanical devices can be substituted therefor and be within the scope and purview of my invention.

C is a cam, pivoted within and near one end of the section A, having an arm C projecting 70 outwardly, as plainly seen in the drawings. When said cam is in the position shown in Fig. 2, the band B will be free to slide backward and forward within the section A, its outward progress being limited by contact of 75 detents b b , which prevent its passage beyond the cam. When, however, the arm C is turned downwardly upon the upper surface of the section A, said cam will forcibly impinge 80 against the band B and securely hold it within 8c the tubular section, whereby the bracelet will be maintained of any required circumferential dimensions. By simply lifting up the cam-handle (see dotted lines, Fig. 1) the cam will assume the position shown in Fig. 2, releasing 85 its pressure from the band B, which will be thus free to be extended its full length until stopped by contact of its limiting detents with the cam C.

The section A is shown in the drawings as 90 rectangular in cross-section, but it may be spherical, arched, or of any desired shape, as taste or convenience may dictate, and the band B can be coincidentally shaped to pass within a tubular section of any conformation.

Having thus described my invention, what I claim, and desire to secure by Letters Patent of the United States, is—

1. A bracelet having a main tubular section 100 A, an extensible band B, permanently connected to said section at one end, its opposite end provided with terminal limiting-detents b b , being inserted within the main section, in

combination with cam C, pivoted at one end of said section, having an outwardly-extending arm, whereby said cam can be turned to grasp and release the extensible band at any position of its length within the tubular section, substantially as described.

2. The within-described extensible bracelet consisting of a main tubular section having at one end, within said section and pivotally connected thereto, a locking-cam provided with an outwardly-extending integral arm, all

5 in combination with a sliding band firmly

connected to one end of the main section, its opposite end, provided with limiting-stops, being loosely inserted within said tubular section and free to travel therein, substantially as described. 15

In testimony that I claim the invention above set forth I affix my signature in presence of two witnesses.

JAMES ROTHSCHILD.
